H. GARRISON

CAN OPENER

Filed Aug. 31, 1925

Inventor:
Herman Garrison.

By Chas. Williamson
Fifty.

UNITED STATES PATENT OFFICE.

HERMAN GARRISON, OF CHICAGO, ILLINOIS.

CAN OPENER.

Application filed August 31, 1925. Serial No. 53,539.

The object of this invention is, to provide a way to use a longer knife than is at present employed on that can opener which operates as a lever of the second class, and 5 comprises a handle, a stock, modified at the end to ride the crimp of a can and afford a fulcrum thereon, and a downwardly offset uppercut knife, which always extends somewhat beyond the fulcrum.

10 An examination of commercial openers of this type will show an almost uniform length of one inch for the cutting edge.

Referring to the drawing forming a part hereof:

15 Fig. 1 is a diagram which shows in outline a side view of a knife such as I employ, with a cutting edge of one and one-half inches.

Fig. 2 shows a cutting edge with its usual 20 length of one inch.

25 Fig. 3 is a side view of my can opener, showing the handle, 1^a, the stock 2^a, set into the handle, and knife 3^a, riveted to the stock. The cutting edges are indicated by a double line. The upper edge is shown 30 with a reentrant curve at 9^a, and the cutting edge is extended up the shank at 5^a, so as to engage the tin at an advantageous angle at the beginning of each kerf. The jog at 4^a serves to arrest the downward movement of 35 the entering knife at the point from which it is to be moved forward into operative position. The prod 11, made from the same blank as the knife, may serve as a bottle opener.

40 Fig. 4 is a view of the front end, showing the grooved fulcrum, and applies equally to Figs. 3 and 6.

Fig. 5 shows at 7^a a blunting of the forward part of the upper edge, the positional 45 relation of the blade to the stock being determined by Fig. 3.

Fig. 6 illustrates by a top plan view a one-piece construction for handle and stock, with the cutting blade laterally curved

throughout its length, the fulcrum being 45 located on the bent portion of strip metal at 10.

After the knife, in the process of insertion, has reached the position shown by Figs. 1 and 2, it becomes necessary to bend or 50 break a certain amount of tin in order to force the heel of the knife into the can. The amount of tin encountered in Fig. 1 will render insertion impossible.

I meet this difficulty by two modifications: 55 I sharpen the back of the blade as at 8^a so as to cut the obstructing tin, and blunt the forward part of the upper edge as at 7^a so as to afford a fulcrum for prying the knife down into the can.

Two other changes in the form of the knife, as usually made, are essential to its 60 successful operation if it is to be much lengthened, viz: a lateral curvature of the blade, and a rearwardly concave outline of 65 the upper cutting edge.

I claim:

A can opener in the form of a lever of the second class, having a guiding fulcrum 70 formed by a recess at the end of a handled stock, and a downwardly offset uppercut knife secured by its shank to the stock and extending forward past the guiding fulcrum; the blade of said knife being laterally curved in the direction of its length, having 75 an additional cutting edge on its lower margin, and having its upper cutting edge rearwardly concave in outline; that part of 80 said blade which projects forward beyond the guiding fulcrum having its upper marginal contour practically continuous in 85 direction, and being provided with a blunt upper wall adjacent to the point of the blade; and the upper face of said wall having a lateral dimension substantially equal to the thickness of the body of the blade."

HERMAN GARRISON.
